UNITED STATES PATENT OFFICE.

GEORGE BINET DOREY, OF MONTREAL, QUEBEC, CANADA.

FRICTION DRAFT RIGGING.

Application filed December 7, 1921. Serial No. 520,658.

To all whom it may concern:

Be it known that I, GEORGE BINET DOREY, a subject of the King of Great Britain, and residing in the city of Montreal, Province 5 of Quebec, Dominion of Canada, have invented certain new and useful Improvements in Friction Draft Rigging, and do hereby declare the following to be a full, clear, and exact description of the same.

10 My invention relates to improvements in friction draft riggings of very high frictional capacity as used in railway cars and the like for the purpose of absorbing shock, and is especially related to that class where- 15 in frictional elements are used to displace other frictional elements a greater distance and at a relatively greater speed.

An object of my invention is to provide a 20 friction draft rigging having shoes in reciprocal engagement with a column member and to provide means whereby the springs used for the purpose of returning the gear to normal release position after compression will exert a force substantially 25 at right angles to the line of motion of the said shoes.

Another object of my invention is to provide means whereby the shoes will be caused 30 to travel in unison. A difficulty hitherto experienced in gears of this type has been the liability of one of the wedges moving in advance of the other and thus disturbing the equilibrium of the mechanism.

A main object of this invention is to provide 35 a draft rigging wherein pressure transmitting members having a comparatively short travel and travelling at a slow speed will displace other members a greater distance and at a greater speed.

40 A further object of the invention is to provide a more certain release of the draft rigging.

Further my invention consists in certain 45 novelties of design and combination of parts, which will be more particularly pointed out in the annexed specification and claims.

The accompanying drawings illustrate an example of the embodiment of the invention as applied between the sills of a railway car.

50 Figure 1. is a longitudinal sectional view through the complete gear as assembled, the

parts being in the normal release or extended position.

Figure 2. is a view similar to Figure 1. except that the gear is shown in the fully 55 compressed position.

Figure 3. is a perspective view of one of the friction shoes.

Figure 4. is a perspective view showing the 60 casing in section.

Figure 5. is a perspective view of the central friction member or column.

Figure 6. is a perspective view of one of the wedge pressure transmitting members.

Figure 7. is a perspective view of one of 65 the wedge resistance members.

Figure 8 is a longitudinal sectional view showing the draft rigging in the first stage of the release operation of the gear with the column withdrawn from its seating and 70 the counter spring compressed.

In the drawings 2 represents the drawbar 75 of the coupler connected by means of key 3 to the yoke 4. in the usual manner, the yoke embracing casing 5 and the whole being located between the center sills 6 and 7. In the illustration the casing is shown as abutting against front stops 8 through the medium of follower 9 while the rear of the rigging abuts against rear stops 10 through 80 the medium of follower 11.

The main casing 5 is preferably formed 85 of rectangular shape and open at one end and for a portion of the sides. The end walls of the casing 12 are oppositely inclined converging towards the longitudinal center of the draft rigging thereby presenting a wedged shaped projection within the casing. This wedged shaped portion is slotted at 13 to permit the passage of the spring rod 19 90 through the gear. Beyond the slot a pocket 14 is formed for the reception of the rounded end of the column 16. The column 16 is extended lengthwise of the draft rigging as at 17 and passes through a hole in the pocket 95 at the end of the casing designated in the illustration as 15. The outer ends of the casing are formed with beveled walls 20 and a recess 21 is formed in each one of these walls for the purpose of allowing a portion 100 of the wedge pressure transmitting members to pass through this portion of the wall.

The side walls of the casing 5 are each provided with an open space at the side for the purpose of receiving the spring rod 19 and other parts constituting the resistance portion of the mechanism.

10 The column member 16 is disposed longitudinally within the casing and is formed at 18 with a rounded end which fits within the pocket 14 of the casing, the end of the column is threaded to receive a nut at 17^a and slotted at 17^b to permit the passage of the spring rod therethrough. The two side walls 16^a constitute bearing surfaces for the friction shoes 22.

15 Friction shoes 22 are preferably two in number and are disposed on each side of the friction column with the bearing surface 23 of the shoes in contact with the bearing surface 16^a of the column.

20 The shoes are preferably made in the form of channels with flanges 24 at the top and bottom, one of which is recessed as at 25 and the other formed with a projection as at 26, the projection on one shoe being adapted to 25 fit within the recess on the flange of the other shoe and thus cause these two members to travel in unison relatively to the column. The recess 25 is deeper than the projection 26 and thus these members are 30 free to move relatively to each other in a transverse direction. A portion of the end of the shoes is removed as shown at 27 to permit the straddling of the spring rod when the shoes have moved to the fully compressed 35 position. The exterior of the shoes are formed wedge shaped at their opposite ends by the inclination of surfaces 28 and 29. Surface 28 is formed to engage with surface 31 of the wedge resistance member 30 while surface 29 is formed to engage with surface 35 of the wedge pressure transmitting member 33.

40 Wedge block pressure transmitting members 33 are disposed on each side of the longitudinal center of the gear and are each formed with a bearing surface 34 constituting one face of a wedge. These surfaces bear on the beveled surface 20 of the casing 5 and for the purpose of providing 45 greater bearing area for the adjacent wedging surface 35 the wedge block pressure transmitting members are formed with recessed portions within which the beveled portions 20 of the casing are disposed. Such a 50 construction extending the bearing surface 35 on either side of the displacement surface 34 provides for great stability. In order to strengthen the ledge 35^a and secure it against bending it is bracketed to the adjacent surface 60 by means of rib 36. The beveled portion of the casing is then channeled at 21 to accommodate this rib. Throughout the length of the wedge blocks a recess is formed 65 between flanges 37 in order that a space may be available to permit the friction column

to pass through when the blocks move inwardly transversely towards each other. Interposed between the drawbar and the wedge block pressure transmitting members and registering therewith as at 33^a is a follower 70 plate 11, the surface 11^a of this member being a friction surface along which the blocks slide during transverse movement.

The resistance part of the mechanism is made up, of the outer springs 39 and inner 75 springs 40 which acting through rod 19 upon wedge resistance members 30 force the friction shoes 22 against the friction column 16 thereby retarding the movement of the wedge block pressure transmitting members. The 80 wedge resistance members 30 are each formed with oppositely inclined ends, one of which 31 registers with surface 28 of the friction shoes while the opposite surface 31^a registers with surface 12 of the casing. A 85 hole 32 is provided through which the spring rod 19 passes. The outer face 31^b is preferably flat and forms a bearing for the springs 39 and 40 through the medium of sleeve 38. The springs hold all the parts in operative 90 engagement through the rod 19 which is threaded at 19^a for the reception of threaded caps 41 by means of which the tension on the springs is readily adjusted. The cap is kept from turning by means of split keys 42 95 passing through the cap and rod.

Within the chamber formed by the sloping walls of the casing there is disposed a counter spring 43 bearing between the casing wall and the washer plate 44 which is 100 held in fixed relation to the column 16 by means of nut 45. The function of this spring will be fully explained hereinafter.

The operation of the draft rigging takes place as follows. In draft or buffing strains 105 the draft gear is compressed by the approach of follower to casing, the rear of the casing abutting against rear stops through the rear follower.

This movement causes wedge block pressure transmitting members 33 to be moved longitudinally into the casing 5 and by reason of the co-acting surfaces between wedge blocks and the beveled surface of the casing at 20 there will also be transverse movement along face 11^a of the follower 11. Resistance to the inward movement as well as to the transverse movement of the blocks 33 is set up by the friction shoes 22 and the wedge resistance members 30 supported by 115 the springs. As the shoes are moved longitudinally on the column the wedge resistance members 30 are also moved longitudinally and outwardly sliding along face 12 of the casing 5 and thereby compressing 120 the springs 39 and 40. During this movement the wedge blocks 33 are moved towards each other thereby bringing the wedge faces 35 closer to each other and creating a squeezing action on faces 29 of the shoes 22 caus- 130

ing these members to move a greater distance and therefore at a greater speed than the coupler, follower and wedge block pressure transmitting members. As this movement 5 progresses the shoes are forced transversely of the gear against the column and adhere thereto with great frictional force thereby providing resistant energy. This frictional adherence is further augmented by the 10 springs which being disposed at right angles to the line of motion of the shoes exert resilient pressure on these members.

In order to provide for more certain release of the parts after compression I have 15 embodied in this invention a novel form of construction which provides for the release of some of the frictional elements independently of the others and further I have used a counter spring in order to return such 20 elements as are moved out of their normal position by the failure of some part of the rigging to release at the right time. In the release of high capacity friction gears there is a tendency for some of the 25 parts to bind especially at the commencement of the releasing operation when the inertia due to frictional adherence must be overcome and the parts set in motion and in order to overcome this difficulty I have 30 made the central column member movable out of its seating for a limited distance and have provided the spring 43 to return it to the normal position as the pressure due to the main springs 39 and 40 decreases. 35 This condition is very clearly illustrated in Figure 8 wherein the spring 43 is shown as being fully compressed with the column 16 withdrawn from its seating and it will be noted that such movement has not been 40 accompanied by any relative movement between the column and the shoes 22. The moment, however, that the counter spring 43 becomes solid and the column 16 is unable to make any further forward movement the shoes 22 commence to slide on the 45 column and as the intensity of the pressure from springs 39 and 40 decreases the counter spring 43 will gradually re-assert itself thereby drawing back the column 16 to its 50 seating and in position for the next compression stroke.

As the shoes 22 move forwardly they force the wedge pressure transmitting members 33 in a forward and outward direction 55 turning the follower 11 with the drawbar to the normal position.

While I have shown and described what I now consider to be the preferred embodiment of my invention it is to be understood 60 that I do not limit myself to the specific construction herein shown as I consider the same merely illustrative and not by way of limitation and I contemplate all modifications that come within the claims appended 65 hereto.

What I now claim is:—

1. A friction draft rigging comprising a column, shoes in reciprocatory engagement therewith, transversely inwardly movable members acting on the shoes and transversely outwardly movable members resisting such movement and adapted to be acted upon by springs angularly disposed to the line of draft. 70

2. In a friction draft rigging the combination with a casing of a column within the casing, shoes in reciprocatory engagement with the column, wedging members in engagement with the casing adapted to move the shoes relatively to the column and 80 springs disposed at right angles to the line of draft resisting such movement. 75

3. In a friction draft rigging the combination with a casing of a column within the casing, shoes in reciprocatory engagement therewith, wedging members in engagement with the casing and adapted to move the shoes relatively to the column, wedging members having engagement with one end of the shoes and springs disposed 85 at right angles to the line of motion of such shoes and resisting movement of the parts. 90

4. A friction draft rigging comprising a casing having one end open and the other end formed with oppositely inclined walls 95 converging towards the longitudinal line of draft, a column within the casing, shoes sliding on the column, wedge block pressure transmitting members engaging the walls of the casing at the open end and adapted 100 to move the shoes, wedge resistance members in engagement with the opposite end of the casing and with the shoes, the said wedge resistance members being acted upon by transversely mounted springs. 105

5. A friction draft rigging comprising a casing having one end open and the other end formed with oppositely inclined walls converging towards the longitudinal line of draft, a column within the casing, shoes 110 sliding on the column, pressure transmitting members operatively associated with the casing side walls at the open end of the casing and adapted to move longitudinally and transversely of the same while moving the aforementioned shoes, wedge resistance members opposing the movement of the shoes, the said wedge resistance members being in wedging engagement with the 115 shoes and with the inclined end of the casing. 120

6. In a friction draft rigging a casing having walls at one end thereof wedge shaped and extended within the casing and the opposite end of such casing formed with 125 flaring walls extending in an opposite direction to those of the wedge shaped end, wedge members in engagement with the side walls, wedge members in engagement with the end walls, friction shoes interposed between 130

the said wedge members and adapted to slide on a longitudinally mounted column, and springs maintaining the parts in operative relation.

5. 7. A friction draft rigging having shoes sliding on a friction member, the said shoes having flanges at the side of the friction member formed with intercalating portions permitting relative transverse movement between the shoes while causing the same to slide on the friction member in unison.

8. A friction draft rigging having shoes sliding on a friction member, the said shoes having flanges at either side of the member, 10 and means to cause the said shoes to travel on the member in unison, the said means comprising a projection formed on the flange of one of the shoes and a recess formed in the flange of the other of the said shoes, the said 20 recess being adapted to receive the projection when the shoes are in operative relation.

9. A friction draft rigging having a series of friction elements adapted to be 25 moved relatively to each other in unison during the compressive action of the rigging, means permitting some of the elements to release independently of the others and a spring adapted to be compressed during the release of these elements and adapted 35 to maintain the various elements in a fixed relation to each other when the rigging is in the normal release position.

10. In a friction draft rigging the combination with a drawbar of a friction member 35 having shoes in sliding engagement therewith and springs disposed at right angles to

the line of draft resisting such movement and wedging means adapted to move the shoes on the member a greater distance than 40 the drawbar.

11. In a friction draft rigging the combination with a drawbar of a friction member having shoes in sliding engagement therewith and springs disposed angularly to 45 the line of draft resisting such movement and means adapted to move the shoes on the member a greater distance than the drawbar.

12. In a friction draft rigging the combination with a casing whereof the interior 50 walls constitute surfaces for longitudinally movable friction members, springs contained on the outside of the casing and disposed at right angles to the line of draft, friction mechanism contained within the casing and 55 adapted to transpose the transverse force of the springs into a longitudinally acting force opposing the movement of the aforesaid longitudinally movable friction members.

13. In a friction draft rigging the combination with a casing whereof the interior 60 walls constitute friction surfaces for longitudinally movable friction elements and friction mechanism contained within the casing and having springs contained outside 65 of the casing and angularly disposed to the line of draft acting thereon.

In testimony whereof I have hereunto set my hand in the presence of two witnesses.

GEORGE BINET DOREY.
